CLAIM

The ornamental design for an accent chair, as shown and described.

DESCRIPTION

FIG. 1 is a perspective view of an accent chair showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The heavy weight dash-dash broken lines depict stitching that does form part of the claimed design. The lighter weight dash-dash broken lines depict portions of the accent chair that form no part of the claimed design.

1 Claim, 7 Drawing Sheets
